UNITED STATES PATENT OFFICE.

JULIUS KERSTEN, OF DELBRUCK, NEAR COLOGNE, GERMANY.

PROCESS OF PRODUCING ALKALI-METAL HYDROXIDS DIRECTLY FROM ALKALI-METAL CHLORIDS.

1,072,010.

Specification of Letters Patent. Patented Sept. 2, 1913.

No Drawing

Application filed October 18, 1912. Serial No. 726,544.

To all whom it may concern:

- Be it known that I, JULIUS KERSTEN, a citizen of the German Empire, and residing at Dellbrück, near Cologne-on-the-Rhine, Germany, have invented a certain new and useful Improved Process of Producing Alkali-Metal Hydroxids Directly from Alkali-Metal Chlorids, of which the following is a specification.
- 10 My invention relates to processes of producing alkaline hydroxids directly from alkali metal chlorids, and consists in effecting the conversion of the latter by means of hydroxid of lead.
- 15 Hitherto it was generally held that hydroxid of lead exercised no action on alkali metal chlorids. (Cf. Lunge's *Handbuch der Soda-industrie*, 3rd edition, vol. 3, page 197, line 26.) My own exhaustive re-
- 20 searches have, however, led to the surprising result that hydroxid of lead is almost quantitatively converted by means of the alkali metal chlorids, and this reaction therefore fulfills to a great extent the prin-
- 25 cipal requirement desired of a commercial process.
- Further advantages of my process are, firstly, that the chlorin present in the alkali metal chlorids is not lost, and, secondly,
- 30 that the chlorid of lead which forms during the reaction can be reconverted into hydroxid of lead without difficulty or appreciable loss and can be used again in this form.
- 35 The known modes of producing alkali metal hydroxids chemically directly from their chlorids, e. g. by means of zinc oxid or litharge (cf. the above cited handbook, pages 193-216), have very various defects
- 40 attaching to them. In the first place the yield is very poor; for example, in the oxid of lead process, at most 50% of the sodium chlorid is converted into caustic soda. Further, the oxid of lead can be recovered
- 45 only at considerable loss from the chlorid of lead produced during the reaction, and in addition, this recovered oxid has a much weaker reactive effect than the original.
- Another undoubtedly great advantage of
- 50 my process is that the agents employed for recovering the hydroxid of lead, i. e. nitric acid and ammonia, are recovered in the form of a valuable product, viz., nitrate of ammonia.
- 55 The process according to my invention
- may be represented by the following equation:
- $$2K(\text{or Na})\text{Cl} + 6\text{Pb}(\text{OH})_2 = 2K(\text{or Na})\text{OH} + \text{PbCl}_2 \cdot 5\text{Pb}(\text{OH})_2$$
- The said process is preferably carried out as follows:—A dilute aqueous solution of the alkali metal chlorid having the hydroxid of lead suspended therein is heated for a short time at a temperature when simmering occurs, the solution being stirred around the whole time. About 150 parts of potassium chlorid, or about 120 parts sodium chlorid will be mixed with about 1500 parts hydroxid of lead. The basic chlorid of lead which results is separated in a suitable manner from the alkali lye, washed, and then dissolved in nitric acid. The solution thus obtained, which contains lead nitrate and hydrochloric acid dissolved in it, is then evaporated to dryness, the hydrochloric acid being given off and condensed; the hydroxid of lead is then precipitated by ammonia from the lead nitrate solution and can be again used to convert a further quantity of alkali metal chlorid into alkaline hydroxid.
- Although it is preferable to heat the dilute aqueous solution of the alkali metal chlorids having the hydroxid of lead suspended therein, the application of heat is not essential to my process. The reaction described takes place at ordinary temperatures, though much more slowly than with the application of heat.
- I claim:
1. A process of producing alkali metal hydroxids directly from alkali metal chlorids which consists in mixing an aqueous solution of an alkali metal chlorid with hydroxid of lead, whereby an alkali metal hydroxid containing basic chlorid of lead is obtained, and in separating the chlorid of lead from the alkali metal hydroxid.
  2. A process of producing alkali metal hydroxids directly from alkali metal chlorids which consists in heating an aqueous solution of an alkali metal chlorid containing hydroxid of lead, whereby an alkali metal hydroxid containing basic chlorid of lead is obtained, and in separating the chlorid of lead from the alkali metal hydroxid.
  3. A process of producing alkali metal hydroxids directly from alkali metal chlorids which consists in heating an aqueous

solution of an alkali metal chlorid containing hydroxid of lead, whereby an alkali metal hydroxid containing basic chlorid of lead is obtained, and in separating the chlorid of lead from the alkali metal hydroxid, in recovering the hydroxid of lead from the basic chlorid of lead, and in converting another aqueous solution of said alkali metal chlorid into an alkali metal hydroxid

by means of the recovered hydroxid of lead, 10 and so on.

In testimony whereof, I affix my signature in the presence of two witnesses.

JULIUS KERSTEN.

Witnesses:

MARIA PALMEN,
OSCAR DEPNER.
